Patented Jan. 5, 1909.

UNITED STATES PATENT OFFICE.

PETER G. TOEPFER, OF MILWAUKEE, WISCONSIN.

COOLING STRUCTURE.

No. 908,905.

Specification of Letters Patent.

Patented Jan. 5, 1909.

Application filed January 6, 1908. Serial No. 409,540.

To all whom it may concern:

Be it known that I, PETER G. TOEPFER, a citizen of the United States, and resident of Milwaukee, in the county of Milwaukee and State of Wisconsin, have invented certain new and useful Improvements in Cooling Structures; and I do hereby declare that the following is a full, clear, and exact description thereof.

10 My invention relates to cooling structures of the kind requiring evaporation of water from an absorbent material for reducing temperature therein; its object being to provide simple, economical and efficient structures of the kind aforesaid, the same being preferably knockdown to facilitate transportation and storage.

Hence said invention consists in certain peculiarities of construction and combination of parts herein set forth with reference 20 to the accompanying drawings and defined in the claims herewith.

Figure 1 of the drawings represents a vertical longitudinal section of a knockdown 25 cooling structure in accordance with my invention, omitting the absorbent material employed in connection therewith, Fig. 2, an end elevation of the same partly in transverse section and illustrating the application 30 of said absorbent material, Fig. 3, a horizontal section of a fragment of the structure, this view being indicated by lines 3-3 in Fig. 1, and Fig. 4, a plan view of another fragment of said structure.

35 Referring by letter to the drawings, A indicates each of the end walls of a cooling structure embodying my improvements, these walls being of suitably bent sheet-metal, preferably galvanized iron, and hollow. The walls are preferably contracted at the top and bottom to stiffen the same and economize space with reference to their engagement with stay-frames and spring-clips hereinafter more particularly specified.

40 Each stay-frame B is a suitably bent strip of preferably galvanized iron or steel welded or otherwise joined at its ends, said frame being preferably a parallelogram and stiffened by a partition-strip C of similar material extending transversely of the same midway of its ends. The ends of the frames engage the top and bottom ends of the hollow walls aforesaid, the ends of the walls being notched to accommodate said frames.

45 Spring-clips D are snapped on the ends of said walls to bind the same in connection

with said frames when the structure is set up, these clips being attached to the aforesaid frames or separate from the same as may be most convenient or desirable in practice. 60

The inner sides of the end walls are horizontally slotted, at intervals vertically of the same, for the sliding engagement therewith of sheet-metal shelves E, the same being preferably galvanized or otherwise treated to 65 render them non-corrosive, and to stiffen these shelves, the same are curled at their front and rear edges. The distance between the shelves may be readily varied because of the multiplicity of the slots in the 70 end walls of the structure, enough of each shelf being cut away at its corners to provide for the extension of the same, in the flat beyond its stiffening curls. These shelves may be perforated or otherwise as the trade may 75 demand.

Supported by the upper frame of the structure are pans F for holding water, and a cover G is preferably employed in connection with each pan. Pans H for a similar function are 80 set within the confines of the lower frame of said structure, and the ends of preferably textile absorbent material I, constituting 85 closures for the otherwise open sides of the aforesaid structure, are laid in the upper and lower pans, said absorbent material being clamped between the upper frame and pans F set therein.

By capillary attraction, the water from the upper pans is caused to saturate the absorbent material, and by evaporation of moisture from said material the temperature within the cooling structure is reduced, this cooling being facilitated, because of the dead-air spaces formed by the hollow end walls of 95 said structure. The excess water from the absorbent material is collected in the lower pans to obviate sloppy conditions about the base of the structure.

Cooling structures similar to the one herein 100 shown and described are particularly designed for campers and others not accessible to a supply of ice necessary to the successful use of ordinary refrigerators, or as substitutes for such refrigerators when ice is too expensive, the best results being obtained by exposing the saturated absorbent material to draft.

By employing covers on the upper pans 110 loss of water by evaporation, except from the absorbent material, is trifling and hence said pans require less frequent filling to sup-

ply the water for constant saturation of said absorbent material.

I claim:

1. A cooling structure comprising horizontal upper and lower rectangular frames, hollow walls in connection with the ends of the frames, pans supported by the upper frame, and absorbent material caught vertically between the upper frame and pans to extend 10 into the latter and constitute closures for the otherwise open sides of the structure.

2. A cooling structure comprising horizontal upper and lower rectangular frames, and hollow walls in connection with the ends of the frames, pans supported by the upper frame, other pans set within the confines of the lower frame, and absorbent material caught vertically between the upper frame and upper pans to extend into all the pans 20 and constitute closures for the otherwise open sides of the structure.

3. A cooling structure comprising hollow end walls of suitably bent sheet metal having the inner sides horizontally slotted at intervals vertically thereof and shelves having sliding engagement with opposite slots.

4. A cooling structure comprising hollow end walls of suitably bent sheet-metal upper and lower frames in connection with the upper and lower ends of the walls, and shelves having sliding engagement with opposite inner side slots of said walls.

5. A cooling structure comprising hollow end walls contracted at the top and bottom, upper and lower rectangular frames engaging recesses provided in the ends of the walls, spring-clips having snap-engagement with said walls over the frames, and shelves having sliding engagement with opposite inner side slots of said walls.

6. A knockdown cooling structure comprising hollow end walls contracted at the top and bottom, upper and lower rectangular frames engaging recesses provided in the ends of the walls, means for clamping the walls in connection with the frames, shelves having sliding engagement with opposite inner side slots of said walls, pans supported by the upper frame, absorbent material caught between said upper frame and pans and adapted to extend into the latter and constitute closures for the otherwise open sides of the structure, and pans set within the confines of the lower frame to receive the lower ends of the absorbent material.

In testimony that I claim the foregoing I have hereunto set my hand at Milwaukee in the county of Milwaukee and State of Wisconsin in the presence of two witnesses.

PETER G. TOEPFER.

Witnesses:

HERMAN PFEIL,
PETER ADUANSEN.
